UNITED STATES PATENT OFFICE

2,448,390

ROCKING HORSE

Edward U. Pugh, Garfield, N. J.

Application April 5, 1944, Serial No. 529,647

6 Claims. (Cl. 272—53)

1

This invention relates to a toy or rocking horse as used by children for amusement.

It is particularly aimed to provide such an article as will not only rock forward and backwards, but will have a second or additional forward movement and backward movement, both caused by the rocking of the toy or article by a child seated thereon.

Further, it is aimed to provide an exceedingly simple and durable construction, one which will not tip over, one which may be manufactured at minimum cost, and a structure which may be caused to advance to the right or left through the momentum of the body of the rider.

The more specific objects and advantages will become apparent from a consideration of the description following taken in connection with accompanying drawings illustrating an operative embodiment.

In said drawings—

Figure 1 is a plan view of the rocking horse;

Figure 2 is a view in vertical section with one side removed;

Figure 3 is a vertical section taken on the plane of line 3—3 of Figure 2;

Figure 4 is a vertical section taken on the plane of line 4—4 of Figure 2; and

Figure 5 is a fragmentary inverted plan view.

Referring specifically to the drawings wherein like reference characters designate like or similar parts, 10 generally designates a body which may be made in any suitable size or configuration, to simulate a horse, any other animal or object. As shown, the body has opposite side members at 11 which preferably diverge downwardly as best shown in Figures 3 and 4. The lower edges of such side members 11 are convex at 12 so that they constitute rockers. These side members may be painted or delineated in any suitable manner to aid in carrying out the representation or simulation of a horse, other animal or object, and any of the parts may similarly be painted or finished with the same end in view.

End pieces 13 are adapted to be secured in place between the side members 11 by glueing, nailing, or in any suitable manner.

I also employ a crown strip 14 disposed between and fastened to the side members 11 at the top and this strip may be continued and finished in representation of a horse's head 15. A horse's tail element 16 may be fastened in any suitable manner in a socket 17 of such strip 14.

An axle 18 is rotatably mounted by and between the side members 11 slightly closer to the front than to the rear, and a pair of wheels or rollers

2

19 are journaled thereon and extend slightly below the surface 12. A spacing sleeve 20 is mounted on the axle 18 between the rollers 19 and the latter are further positioned by pegs 21 engaging the axle.

Forwardly of the axle 18 and above the same, a cross brace 22 is interfitted with and secured to the side members 11 at 23. An inclined steering post 24 is journaled in an opening 25 in the crown strip or block 14 and in an opening 26 in the cross brace 22. Below the cross brace, post 24 as at 27, is fastened to an axle 28 and a spacing sleeve 29 surrounds the post between the cross brace 22 and the axle. Such axle rotatably mounts wheels 29 whose peripheries extend slightly below the rocker surfaces 12. The wheels 29 are held in place on axle 28 by terminal flanges 30, pins 31 and spacing sleeves 32.

A saddle 33 is provided on the crown block or strip 14 to enable seating of the child in proximity to a bar 34 which is fastened to the post 24 in such manner as to enable turning of the bar 34 and steering of the post 24 and wheels 29. A collar 35 surrounds the post 24 between the block 14 and bar 34 and flexible straps or the equivalent 36 may extend to the head of the animal from the bar 34. Stirrup members 37 may be located on the outer surfaces of the side elements 11.

30 A lever 38 is freely suspended from a short shaft 39 anchored in the crown block 14 and side members 11 approximately centrally and adjacent the top. It is desired to hold the lever 38 so that in its movement it will not rub against the inner surfaces of the side members 11 and to this end, the lever 38 is bifurcated to provide a slot 40 receiving and fitting the crown block 14 as best shown in Figure 4. The lower end of the lever has an arcuate surface 41 as shown, which at the 10 rear end, is slightly lower than the rocker edges 12 as shown in Figure 2. It is also to be noted that adjacent the lower edge, lever 38 is cut away at the front as at 42 to enable the lever to move closer to the roller 20 and assume a vertical position.

In using the toy, the child is seated at 33 and he rocks his body forward and backward to impart corresponding movement to the toy in view of the rocker edges 12. The device will travel 50 either indoors or outdoors on a concrete sidewalk, a boardwalk, or any reasonably hard flat surface. As the child rocks, he may steer the toy by moving the bar 34 and in addition to the rocking movement, when he moves forward and backward, the lever 38 will by gravity move

from the full-line position of Figure 2 to the dotted-line position of the same figure, serving as a strut to give the horse an extra lunge so that the horse will be given two distinct forward moves, one as it rocks forward and one as it is rocked backward.

Various changes may be resorted to provided they fall within the spirit and scope of the invention.

I claim as my invention:

1. A structure of the class described comprising a body having a rocking surface, a lever suspended thereon extending slightly below the rocking surface, and roller means carried by the body and extending slightly below said rocking surface in advance of the lever, said roller means having a fixed axis disposed relatively close to the center of gravity of said body.

2. A structure of the class described comprising a body having a rocking surface, a lever suspended thereon extending slightly below the rocking surface, roller means carried by the body and extending slightly below said rocking surface in advance of the lever, said lever being cut away, at a portion thereof to enable it to more closely approach the roller means.

3. A structure of the class described comprising a body having a rocking surface, a lever suspended thereon extending slightly below the rocking surface, roller means carried by the body and extending slightly below said rocking surface in advance of the lever, said lever being cut away at a portion thereof to enable it to more closely approach the roller means, a saddle on the body, and a steering roller means carried by the body and operable by the occupant of said seat.

4. A structure of the class described comprising inclined side members, said members having rocker edges, crown means connecting said side members, a lever freely pivoted to the crown means, said lever having a slot fitting it to the crown means to avoid contact with the inner surfaces of the side members, said lever being cut away at a portion thereof to enable it to more closely approach the roller means, and said lever

having its lower end extending slightly below the rocker edges.

5. A structure of the class described comprising inclined side members, said members having rocker edges, crown means connecting said side members, a lever freely pivoted to the crown means, said lever having a slot fitting it to the crown means to avoid contact with the inner surfaces of the side members, said lever having its lower end extending slightly below the rocker edges, a steering post journaled in the crown means, and steering roller means mounted by the steering post and extending slightly below the rocker edges.

10 15 20 25 30 35 40 45 50 55 60 65 70 75 80 85 90 95 100

6. A structure of the class described comprising inclined side members, said members having rocker edges, crown means connecting said side members, a lever freely pivoted to the crown means, said lever having a slot fitting it to the crown means to avoid contact with the inner surfaces of the side members, said lever having its lower end extending slightly below the rocker edges, a steering post journaled in the crown means, steering roller means mounted by the steering post and extending slightly below the rocker edges, a cross bar between the side members in which the post is journaled, roller means behind the steering rollers, said lever being cut away to enable closer relative movement of the same and roller means.

EDWARD U. PUGH.
